UNITED STATES PATENT OFFICE.

NICHOLAS W. SHERMAN, OF COLDWATER, MICHIGAN, ASSIGNOR OF ONE HALF TO DANIEL ELLIS, OF SAME PLACE.

TWO-WHEELED VEHICLE.

SPECIFICATION forming part of Letters Patent No. 325,772, dated September 8, 1885.

Application filed July 13, 1885. (No model.)

To all whom it may concern:

Be it known that I, NICHOLAS W. SHERMAN, a citizen of the United States, residing at Coldwater, in the county of Branch and State 5 of Michigan, have invented certain new and useful Improvements in Combinations in a Two-Wheel Cart; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 In the annexed drawings, Figure 1 represents a vertical sectional view taken centrally through my improved two-wheel vehicle, and Fig. 2 is an elevation of the rear end of the vehicle.
20 This invention relates to two-wheel vehicles; and it consists in certain novel improvements in mounting the seat upon the thills and a semi-elliptic spring secured to a spring-bar by a joint, *b*, to which the seat-bars the 25 foot-rest is secured, as will be fully understood from the following description, when taken in connection with the annexed drawings.

I am aware that seat-supporting bars attached by a simple pivot-joint have been used in combination with springs having foot-rests and attached to a spring-bar by the rear supporting-spring.

It will be seen from the following description 35 that my main object is to construct an exceedingly light vehicle which possesses great strength and durability.

A A designate the wheels of the vehicle, and B the axle, as shown in Fig. 2, which 40 latter is preferably arched, as shown.

C C are the thills, which are curved, as shown in Fig. 1, and connected rigidly together by a transverse thill-bar, C', rigidly secured to the axle B by clips *e e*, and also 45 provided with bracing-rods C'', which extend from said clips to the thill-bar C'.

D indicates the seat, which is rigidly secured upon the rear ends of two inclined seat-bars, E E, that are attached to the thills C C at 50 suitable joints, *a*.

Between the seat D and the joints *a* the seat-bars E E are fastened or secured by

knuckles at *b b* upon a horizontal spring-bar, F, which is supported upon a compound semi-elliptic spring, G, and rigidly secured to this 55 spring by means of clips *b' b'*. The extremities of the said spring G are connected by shackles *c c* to clips *d d*, which are secured to the thills C C.

J designates a slatted foot-stand, which constitutes the floor and the dash-board. The 60 slats of this foot-rest are secured to curved rods K K, the front ends of which are secured to the spring-bar F and the rear ends to the seat-bars E E immediately beneath the 65 seat D.

It will be seen from the above description that the foot-stand, the seat-bars, and seat, and also the spring-bar, are all sustained upon the central arched portion of the semi-elliptic 70 spring, which in turn is suspended by shackles from the thills.

It will also be seen that the seat is sustained against undue forward and backward movements by the seat-bars E E, which also 75 resist forward and backward movement and strain on the spring, but allow free vertical movement of the seat.

It will be observed that the joint *a* is a loose or shackle joint, and that it is designed, in 80 combination with the spring G, to allow a free motion, both vertically and longitudinally—to wit, a slip joint.

Having described my invention, what I claim, and desire to secure by Letters Patent, 85 is—

The combination, with the thills attached, as described, to the axle B, of the seat-bars E, loosely attached to the thills at *a*, and bearing a seat, D, the curved rods K, provided with 90 foot-slats and secured to the seat-bars, and also to the spring-bar F, the spring G, attached, as described, to the thills, and also to the spring-bar, and the joints *b*, connecting the latter to the seat-bars, all constructed and 95 adapted to operate as and for the purposes described.

In testimony whereof I affix my signature in presence of two witnesses.

NICHOLAS W. SHERMAN.

Witnesses:

CHARLES F. RUGGLES,
DUDLEY M. WELLS.
